UNITED STATES PATENT OFFICE

148,484

DESIGN FOR A TOILET TISSUE DISPENSER

Benjamin G. Roche, Quebec, Quebec, Canada

Application September 30, 1946, Serial No. 133,660

Term of patent 14 years

(Cl. D4—3)

To all whom it may concern:

Be it known that I, Benjamin G. Roche, subject of the King of Great Britain, residing at 933 St-Foy Road, city of Quebec, Province of Quebec, Dominion of Canada, have invented a new, original, and ornamental Design for Toilet Tissue Dispenser, of which the following is a specification, reference being had to the accompanying drawing, forming part thereof.

I claim:

The ornamental design for a toilet tissue dispenser, as shown.

BENJAMIN G. ROCHE.
